P. F. WILLIS

GAS BURNER OR TORCH

Filed June 23, 1919

Inventor:
Prior F. Willis,
By George A. Pennington,
his Atty.

UNITED STATES PATENT OFFICE.

PRIOR F. WILLIS, OF ST. LOUIS, MISSOURI.

GAS BURNER OR TORCH.

Application filed June 23, 1919. Serial No. 306,139.

To all whom it may concern:

Be it known that I, PRIOR F. WILLIS, a citizen of the United States, residing in the city of St. Louis and State of Missouri, have invented a new and useful Improvement in Gas Burners or Torches, of which the following is a specification.

This invention relates to blow-pipes, welding torches, cutting torches, and, in fact, any and all instruments or tools which are used to combine and burn a mixture of oxygen and a combustible gas. It has for its principal object to prevent the occurrence of "flash-backs" or "back-fires" and at the same time secure the best or most desirable normal mixture of the gases, from an efficient operative and economical standpoint, in blow-pipes, torches and appliances of the character above pointed out, and more particularly in oxy-acetylene welding and cutting torches or burners which use acetylene as the combustible and oxygen as the supporter of combustion, and in which latter devices the gases are delivered through separate channels or conduits to a mixing chamber from which the commingled gases flow to the tip of the nozzle and are ignited at the orifice thereof.

So far as I am aware, there has never been constructed a torch or tool which, under certain conditions hereinafter stated, is not subject to the phenomenon known as a "flash-back" or "back-fire," while at the same time maintaining a "neutral" flame under abnormal conditions.

Ordinarily, the term "flash-back" or "back-fire" means the burning of the commingled gases in the mixing chamber; but, under extreme conditions, the burning may penetrate the handle of the torch, the hose, or even the regulators. Obviously, this is objectionable, for when the same occurs, the torch is unworkable and it is necessary to shut off at least one of the gases and usually both of them and then re-light the torch.

Commercial oxygen is usually furnished compressed in tanks and it can be obtained of a purity ranging from about 96% to as high as 99%. When absolutely pure it has a specific gravity of 1.105, assuming air to be unity or one. If the oxygen is produced by the electrolytic decomposition of water, the impurity will be hydrogen, the lightest of gases. If the oxygen is made by the liquid air process, the impurity will be nitrogen, a gas which is slightly lighter than air.

It follows from the above that the introduction of either hydrogen or nitrogen to commercial oxygen would reduce its specific gravity so that it would approach more closely the weight of air.

Commercial acetylene is obtained either from a generator making and delivering the gas at a pressure not greater than fifteen pounds, or from so-called safety tanks in which the acetylene has been dissolved by means of acetone under an initial pressure of about two hundred fifty pounds, but reduced by means of regulators to the pressure required by the burner in use. The specific gravity of chemically pure acetylene, is .91, assuming air to be unity.

Acetylene used commercially for welding, if taken from a generator, will carry, held in suspension, a certain amount of water vapor. This amount of water vapor will vary considerably, depending upon the rate of generation, weather conditions, etc. On the other hand, if the gas is taken from a compressed or so-called safety tank, it will carry, held in suspension, a certain amount of the solvent called acetone. The introduction of water vapor or acetone, as the case may be, will materially increase the specific gravity of the gas.

If the acetylene or the oxygen used commercially approach chemical purity, attention should be given to the differences in specific gravity and accurate allowances made either in the pressure under which the gases operate or in the sizes of the openings through which the gases pass into the mixing chamber.

It has long been known that a mixture of acetylene and oxygen, when lighted, may travel at a rate of three hundred thirty feet per second, and it must, therefore, be obvious that the two gases, when lighted, should be under a pressure sufficient to insure the mixture escaping from the nozzle or tip of the torch at this speed at least.

It has also long been known that if a combustible is enriched with air or oxygen beyond the proper amount it will "flash-back" or "back-fire" and if the amount of air or oxygen is sufficiently decreased it is practically impossible to create a "flash-back" or "back-fire." This is true of the well known Bunsen burner and equally so of the oxy-acetylene torch, as well as other burners of similar character.

It is further recognized that two and one-half volumes of oxygen are necessary to

completely consume one volume of acetylene. Theoretically, one and one-half volumes of oxygen can be taken from the atmosphere and the other one volume from the oxygen supply to the mixing chamber.

Now, it has been observed by me, and undoubtedly by others, that a strongly carbonizing flame (that is, one having too much acetylene, or, putting it the other way around, not enough oxygen), if operating under sufficient pressure, is free from "flash-backs."

It would naturally suggest itself that, if the prevention of "flash-backs" was the one and only desideratum, the acetylene ports into the mixing chamber should be of such size as to permit a higher pressure than the oxygen. In that case, there would at no time be an excess of oxygen, but just as surely there would be a surplus of acetylene as long as the exit of the nozzle was partially closed or the free flow of the gases therefrom interrupted, and this condition might continue indefinitely.

An excess of acetylene in the flame will be lacking in heat besides depositing carbon in the metal, thereby making it hard and brittle. On the other hand, an excess of oxygen will oxidize or burn the metal. Therefore, unless the mixing chamber, the exit of the nozzle, and the various openings into the mixing chamber are so arranged and proportioned that, under proper pressures, the mixed gases will emerge from the nozzle so as to produce a neutral flame, the torch will be valueless, regardless as to its liability to back-fire or not.

It is understood that there are two things which practically control the amount or volume of gas passing through an opening and they are the size of the opening and the pressure. If a certain volume of acetylene travelling at a certain speed is required for a particular size tip, having determined upon the size of the opening, it is an easy matter to obtain the necessary pressure to produce the speed. If a higher pressure should be desirable, and the volume of gas is to remain constant, the size of the opening is decreased, whereas, of course, if a lower pressure is wanted the opening is enlarged.

If the oxygen entering the ordinary mixing chamber is under a pressure higher than the acetylene, and the nozzle of the torch becomes momentarily partially obstructed by flying particles or by touching the metal being treated, or from other causes, it would appear that the oxygen flowing under the higher pressure exerts itself more forcibly, with the result that the gases in the mixing chamber contain a greater amount of oxygen than of acetylene. Where the pressure on the oxygen and the acetylene is the same, this condition still exists, although not to

the same extent, probably because the oxygen, in spite of impurities in the acetylene, is still the heavier and predominates by reason of this fact, with the result that there is in the mixing chamber an ideal mixture 70 for a "flash-back" or "back-fire" and that is what usually occurs.

Now, in carrying out my invention, I provide means whereby the oxygen, for a limited space of time, will not force itself through 75 the zone of mixed gases and predominate. This consists partly in constructing the openings for the acetylene and the oxygen so that they will operate under practically the same pressures. By this I mean that 80 it is preferable to have the pressures of the two gases substantially equal and in that way obtain a purely mechanical, balanced mixture, free from injector or ejector principle. However, a very slight excess of pressure on the acetylene or the oxygen would 85 not materially alter the conditions.

In the accompanying drawing are illustrated two practical adaptations of the invention to oxy-acetylene welding torches, the 90 one being embodied in a tip construction and the other in a handle construction, but, as hereinbefore stated, the invention may be utilized in a wide variety of forms, such as those in which the mixture is effected 95 within the tip, within the handle, or in front or behind the handle, or in the head of the torch rather than in the tip, and in torches or burners utilizing combustibles other than acetylene.

Figure 1 of the drawing shows a preferred structure of torch head and detachable tip in longitudinal section;

Figure 2 is a view of a modification of the tip detached; and

Figure 3 is a view, partly in elevation and partly in section, of the torch in which the mixture is effected in the handle.

Referring now more particularly to Figure 1 of the drawing, the numeral 1 designates the head of an oxy-acetylene welding torch having an oxygen supply passage 2 and an acetylene passage 3 therein, and having attached thereto the conducting pipes 4 and 5, which respectively communicate 110 with said passages 2 and 3, and are attached, in practice, to the usual handle 100 at their outer ends, which latter is, ordinarily, obviously provided with suitable gas passages and cut-off valves and has the usual 115 hose connections with the respective sources of gas supply.

The head 1 has a bore 6 therethrough for the reception of the shank portion 7 of a nozzle member or tip 8. The nozzle or tip, 125 as shown, has a tapered shoulder or seating portion 9 at the root of the shank portion 7 which fits a correspondingly tapered or flared seat 10 at the adjacent end of the bore 6 of the head 1, while the end portion of 130

the shank is screw-threaded, as at 11, to enter a screw-threaded axial socket 12 in a closed plug 13, which latter is tapered, as at 14, to fit a correspondingly flared seat 15 in the adjacent end of the bore 6.

The nozzle or tip 8 has an axial bore 16, the upper portion of which constitutes the mixing chamber for the oxygen and acetylene. A port 17 in the nozzle or tip opens 10 at its inner end into the bore 16 and at its outer end through the tapered seat portion or shoulder 9 at a point to register with an annular groove 18 provided in the flared seat portion 10 in the bore 6 of the head 1, 15 and with which groove the acetylene passage 3 communicates.

The oxygen passage 2 communicates with the bore 6 of the head 1 at a point between the flared end portions 10 and 15 thereof; 20 and the shank portion 7 of the nozzle or tip being of a diameter less than that of the bore 6 an annular receiving chamber 19 is afforded for the oxygen, and between which chamber and the bore 16 of the nozzle or tip communication is had through the port 20 above or behind the acetylene port 17.

By the construction above described, the nozzle or tip is readily attached to and detached from the head 1, and at the same time, 30 absolute seals are provided to prevent the escape of the gases to the atmosphere as well as to prevent the commingling of the two gases before they enter the ports 17 and 20 respectively.

As shown in Figure 1, the bore 16 of the nozzle or tip extends entirely therethrough and is closed by the plug 13, thereby constituting a relief chamber 21 above or behind the oxygen inlet.

It has been found that when the torch is operating normally, there is produced a partial vacuum in the chamber 21, as compared with the pressure in the remainder of the bore 16 ahead of the oxygen inlet. The inflowing oxygen into the nozzle or tip, by reason of its speed, tends to draw or suck out any gas that may have accumulated in this relief chamber 21. Should the orifice of the nozzle or tip become partially obstructed, the acetylene port being ahead or in front of the oxygen port and the pressures of the two gases being substantially the same, the tendency is to slow up the incoming oxygen and divert it up into the relief chamber 21 above or behind the oxygen inlet, with the result that the mixture of the gases in the mixing chamber, for a limited space of time, continues in the same proportions and the flame remains neutral although of a capacity less than that of the flame obtained before the outlet of the nozzle or tip became restricted. In other words, the flame is still of the same character, but only of a capacity equivalent to that of a 65 smaller sized nozzle or tip.

If the obstruction at the orifice of the nozzle or tip remains the back-fire may then occur, but before this happens the operator has had ample warning by an increased hissing and sputtering that the conditions under which the torch is working are not adapted to good welding.

In most cases, if the operator lifts the torch from the work as soon as he is aware of the abnormal conditions, which are readily observed by the change in the capacity of the flame and its action as above set forth, the obstruction may disappear of itself or be disengaged or discharged from the nozzle or tip by the manual manipulation of the operator, whereupon the original flame is again brought about without necessitating the shutting off of either of the gases and re-lighting the torch as is almost invariably consequent upon the happening of such abnormal conditions in the operation of the ordinary torches or burners of the character as heretofore constructed.

In Figure 2 of the drawing, a modification of the nozzle member or tip is illustrated, in which the relief chamber 21^a is counterbored to a diameter greater than that of the bore proper 16 into which the two gases are normally discharged and mixed; and this relief chamber is closed at the outer end by a plug 22 fitted tightly therein. In this modification, also, an annular groove 18^a is provided in the tapered shoulder or seating portion 9 to take the place of or cooperate with the groove 18 which may or may not be provided in the head 1 as shown in Figure 1, as may be desired.

A further modification is shown in Figure 3, wherein the invention is applied to a torch in which the mixture of the gases is effected in the handle. In this modification the handle 23 has a nozzle extension 24 having the usual conduit 25 for the commingled gases from the mixing chamber 26. The oxygen is discharged into the mixing chamber from an axial nozzle 27, surrounding which is the relief chamber 28, while the acetylene or combustible gas is delivered into the mixing chamber through the port 29 ahead of the oxygen nozzle. In this structure, the action is substantially the same as in the structures shown in Figures 1 and 2, for, under normal conditions, a partial vacuum is created in the relief chamber 28 during the operation of the torch, and the oxygen will back up in said chamber when an obstruction occurs in the outlet from the nozzle 24.

Obviously, the construction admits of considerable further modification without departing from the spirit of the invention which is characterized broadly by the relief of the pressure of the supporter of combustion for a limited period under abnormal working conditions, so as to prevent a "flash-

back" or "back-fire" and during which time the neutral flame is still maintained. In other words, the principal object of the invention is to produce a torch or burner which 5 first of all mixes the gases so that equal or substantially equal volumes of the combustible and supporter of combustion, in the case of acetylene and oxygen being used, or, in the case of other gases, whatever proper 10 proportions may be required to produce a neutral flame, are consumed at the nozzle or tip orifice, and will not back-fire under normal conditions, and yet if something out of the ordinary occurs for a short interval will 15 adjust itself to those conditions and still not back-fire and will maintain the neutral flame, but if the abnormal conditions persist will indicate to the operator that the conditions under which the torch or burner is operating are not conducive to good work.

What is claimed is:

1. In a gas burner or torch of the character described, means for supplying the combustible and the supporter of combustion in the proper proportions and pressures to produce a neutral flame from an orifice of a given capacity, and means for creating a vacuous relief for the supporter of combustion by the operation of the latter flowing 20 into the mixing chamber under normal conditions whereby to maintain the neutral flame under such conditions and wherby, also, the neutral flame continues for a limited period, but of proportionate lesser capacity, upon the occurrence of an abnormal restriction of the orifice.
2. In a gas burner or torch of the character described, a mixing chamber, means for supplying the combustible and the supporter of combustion to said mixing chamber from separate sources and the supporter of 25

combustion being admitted behind the combustible, and a relief chamber communicable with said mixing chamber rearward of the inlet for the supporter of combustion 45 whereby to be evacuated by the operation of the supporter of combustion flowing normally into said mixing chamber.

3. In an oxy-acetylene torch, a mixing chamber having an outlet for a flame of a given capacity, and the inlets for the acetylene and the oxygen being relatively proportioned to each other and to the size of the outlet from the mixing chamber to supply the acetylene and the oxygen in substantially equal volumes and pressures, the inlet for the oxygen being rearward of the inlet for the acetylene, and there being a relief chamber communicable with said mixing chamber and normally evacuated by the 50 operation of the oxygen flowing into the mixing chamber, whereby a neutral flame is maintained during normal operation, and whereby, also, the neutral flame continues for a limited period, but of proportionate 55 lesser capacity, upon the occurrence of an abnormal restriction of the outlet from the mixing chamber for a limited period.

4. In a gas burner or torch of the character described, a mixing chamber, means for supplying the combustible and the supporter of combustion to said chamber from separate sources and the supporter of combustion being admitted behind the combustible, and a relief chamber extending rearward axially of 60 said mixing chamber and being communicable therewith rearward of the zone of entrance of the supporter of combustion.

Signed at St. Louis, Missouri, this 13th day of June, 1919.

PRIOR F. WILLIS.
